BUILDING CONSTRUCTION

Roy V. Yeager, Evanston, Ill.

Application May 14, 1934, Serial No. 725,413

2 Claims. (Cl. 72—66)

This invention relates to building constructions, and has reference more particularly to monolithic floor and ceiling constructions where-in building voids are supported upon structural members.

In the construction of floors and ceilings, the use of bar joists has become quite common because of their relatively low cost and high strength. In using bar joists or other structural members, it is desirable to construct a floor with cementitious floor voids in such a way that the bottoms of the voids present a smooth surface for the application of a coating of plaster, while the tops of the voids form a support for a floor layer of poured cementitious material which also embeds the structural members.

An object of this invention, therefore, is to provide a building construction for use in floors and ceilings which can be erected with a minimum of labor, and which will combine high strength with a low cost of material; also to improve building constructions in other respects hereinafter specified and claimed.

Reference is to be had to the accompanying drawing forming part of this specification, in which

Fig. 1 is a perspective view, partly in section, of my improved floor and ceiling construction.

Fig. 2 is a sectional elevation through a modified form of the floor and ceiling construction.

Fig. 3 is a sectional elevation through one of the cementitious voids used in the building construction, and

Fig. 4 is a sectional elevation through the building construction taken at right angles to the view shown in Fig. 2.

In constructing a floor and ceiling, beams 10 are supported at their ends on the frame work of the building. Said beams are preferably of steel and I-shaped, having lower flanges 11 and upper flanges 12. Bar joists 13 are arranged transversely of the beams 10 and comprise upper chords 14 and lower chords 15. The chords 14 and 15 are preferably I-bars and are connected together by means of obliquely extending bars 16 which are welded to said chords. The ends of the lower chords 15 are bent upwardly to form oblique sections 17, which in turn are then bent outwardly to form bearing sections 18, said sections being welded to the ends of the upper chords 14. A cementitious body 19 is molded about the lower chords 15 and a small portion of the bars 16, said body presenting oppositely disposed shoulders 20. In the form of construction shown in Fig. 2, the height of the body 19 is approximately $\frac{1}{6}$ of

the total height of the bar joist 13. It should be understood that any other type of structural member may be used instead of the bar joist 13.

In order to fill the space between the bar joists 13, I provide a floor void 22 which is composed of an upper wall 23 and a lower wall 24, the bottom surface 25 of which is substantially co-planar with the bottom surface of the body 19 so as to present a flat surface for the reception of a coating of plaster 26. Longitudinal flanges 27 extend along side walls 28 of the voids 22 shown in Fig. 2, said flanges 27 being arranged to engage the shoulders 20 to support the floor void at the proper elevation. The side walls 28 are preferably inclined upwardly and by tilting the floor voids slightly, they can be inserted between the upper chords and then provide a maximum bearing surface between the flanges 27 and the shoulders 20.

A cementitious floor 30 is poured on top of the voids 22 and embeds the bar joist 13 so as to make a substantially monolithic construction. Shoe tiles 31 are positioned about the lower flanges 11 of the beams 10, the bottom surface of said shoe tiles being preferably co-planar with the bottom surfaces of the bodies 19 and voids 22. One end of each void 22 is closed by a wall 32. It should be understood that any type of suitable cementitious material may be used for the voids 22, bodies 19 and floor, such as gypsum, concrete, etc.

In the form of construction shown in Fig. 1, side walls 33 of the floor voids are arranged substantially parallel. In this form of construction, shoulders 34 on the floor voids engage shoulders 35 on cementitious bodies 36. In this form of construction slightly less bearing surface is provided between the shoulders 34 and 35 as it is necessary to make the voids sufficiently narrow in width to pass between the flanges of upper chords 37.

I would state in conclusion that while the illustrated examples constitute practical embodiments of my invention, I do not wish to limit myself precise to these details, since manifestly, the same may be considerably varied without departing from the spirit of the invention as defined in the appended claims.

Having thus described my invention, I claim as new and desire to secure by Letters Patent:—

1. In a building construction, a plurality of bar joists supported in spaced, parallel relation, said joists having upper and lower chords connected by oblique bars, a cementitious body molded about said lower chord and the lower portion of said

- bars, said body forming opposed shoulders, cementitious floor voids spanning a substantial distance between said bar joists and supported at each end on said shoulders, said voids extending 5 below the top chords of said bar joists and extending below said bottom chords in co-planar relationship with the bottom of said body, a plaster layer applied to the bottom surface of said voids and bodies, and a cementitious floor poured 10 above said voids and embedding the projecting top chords of said bar joists.
2. In a building construction, a plurality of bar joists supported in spaced, parallel relation, said joists having upper and lower chords connected by spacing bars, a cementitious body 15

molded about said lower chord and the lower portion of said bars, said body forming opposed shoulders, cementitious floor voids spanning a substantial distance between said bar joists and supported at opposite points on said shoulders, 5 said voids having at least a portion of their upper surfaces extending below the top chords of said bar joists and extending below said bottom chords in co-planar relationship with the bottom of said body, a cementitious layer applied to the bottom 10 surface of said voids and bodies, and a cementitious floor poured above said voids and embedding the projecting top chords of said bar joists.
